(57) **CLAIM**

The ornamental design for a universal tilt tabletop stand, as shown and described.

DESCRIPTION

FIG. 1 is a front isometric view of the universal tilt tabletop stand according to the invention;

FIG. 2 is a rear isometric view of the universal tilt tabletop stand depicted in FIG. 1;

FIG. 3 is a right elevation view of the universal tilt tabletop stand depicted in FIG. 1;

FIG. 4 is a left elevation view of the universal tilt tabletop stand depicted in FIG. 1;

FIG. 5 is a front elevation view of the universal tilt tabletop stand depicted in FIG. 1;

FIG. 6 is a rear elevation view of the universal tilt tabletop stand depicted in FIG. 1;

FIG. 7 is a top plan view of the universal tilt tabletop stand depicted in FIG. 1; and,

FIG. 8 is a bottom plan view of the universal tilt tabletop stand depicted in FIG. 1.

The broken lines shown in the drawings represent portions of the universal tilt tabletop stand that form no part of the claimed design.

1 Claim, 8 Drawing Sheets
